LUG STRAP

W. Irving Bullard, Danielson, Conn., assignor to
E. H. Jacobs Manufacturing Company, Daniel-
son, Conn.

Application April 10, 1936, Serial No. 73,668

1 Claim. (Cl. 139—153)

My present invention is a novel and improved lug strap suitable for use with both an arc- or crescent-shaped lug strap, and a straight lug strap.

5 In my prior application Ser. No. 28,291, filed June 25, 1935, the advantages of an arc- or crescent-shaped lug strap, formed with a longitudinal curve from heel to bolt slots, substantially or approximately following the curved path of travel 10 of the picker stick with which the lug strap is designed to cooperate, results in greatly increased efficiency, longer life and wear, and a saving in power required.

15 In my present improved structure I have discovered that a block or plug in the heel of such an arc-shaped lug strap will operate more efficiently with the surface at the forward or picker stick striking-face of the plug, formed in a curved or arc-shaped contour, non-parallel with 20 and hence diverging from the inner face of the heel of the lug strap.

Heretofore it has been customary in the construction of lug straps with a plug or block at the heel to have the picker-striking face in a 25 plane perpendicular to the sides of the U-shaped arms, and I have discovered that by utilizing a block or plug with the convex striking surface greater increased efficiency is secured in this type of construction, effecting the striking action between the lug strap and picker stick more evenly, 30 uniformly, and in a manner to effectively eliminate vibration and, hence, to increase the smoothness of operation in the striking action.

While these lug straps are usually of textile 35 material, they may also be made of metal, fibre, or reinforced composition.

Accordingly, in my present invention of an improved convex-faced block or plug for lug straps, both straight and arc-shaped, I have shown both 40 these constructions in the accompanying drawing, and wish to claim this feature of the convex-faced block in connection with the arc-shaped lug strap and the straight lug strap, with which it may be efficiently employed whether of 45 textile material, metal, or other structure.

45 Referring to the drawing illustrating preferred embodiments of my present invention,

Fig. 1 is a side view of my novel type of arc-shaped lug strap with the novel convex-faced plug;

Fig. 2 is a plan view of the same;

Fig. 3 is a side view illustrating my novel convex-faced plug in a straight lug strap, and

Fig. 4 is a fragmentary view illustrating the

picker stick and its rocking action, and an arc-shaped lug strap in operative position thereon.

Fig. 5 is a fragmentary view in perspective showing a metal lug strap and a usual type of "hold-up" guide and holder, which may be adjusted on the picker stick to obtain the speed desired.

As shown in the drawing, an arc-shaped lug strap 1, of interrolled textile material, with the usual bolt slots 2—2 formed near the ends of the 10 arms is illustrated, and having a longitudinal arc or crescent-shape between the forward ends of the U-shaped arms, and the heel portion 3 is indicated. These lug straps may be of any suitable length desired. Secured to the heel portion 15 by a bolt 4 is a block or plug 5, having the picker-striking face 10 formed upon a convex curve. The curved striking face 10 may be varied somewhat but should be of suitable proportions to effect a rocking action on the back of the picker stick 12 during the picking operation.

I have illustrated a picker stick 12 in a typical construction at one side of the loom with which it cooperates, the picker stick 12 being attached to the rocker foot 14 adapted to rock upon a base 15, which may be adjustable longitudinally on a support 16, and is held by the spring 17 bolted at 18 to the picker stick 12, and with its other end engaging a bearing 19 attached to a strut 20 on the base 15. The usual guides 21 and 22 are shown, and the picker box 24 at the top of the picker stick 12 is illustrated in partial or fragmentary form.

In Fig. 3 I have illustrated a straight form of lug strap 25 with the usual bolt slots 2 and heel portion 3, and, in this case, with the block or plug 30 secured by the bolt 4 and having a convex picker-striking face 33. In this form, the convex face 33 may be of slightly different contour than that of the convex striking face 10 40 in the arc-shaped form of Figs. 1 and 2, but in both cases the convexity on the striking face of either plug 5 or 30 will insure a smooth, even rocking action between the lug strap and picker stick 12 during the picker operation, eliminating 45 vibration, decreasing wear, and increasing the efficiency of operation.

In Fig. 5 I have illustrated a lug strap 40 of metal, reinforced or the like, having my novel and improved curved striking face on a plug 50 42 held by a bolt 43 and with the bolt slots 44 at the open end of the U arms, plates, or rods. Also I have illustrated at 41 the usual type of "hold-up", or guide, which may be secured to the picker stick at variable heights to thus vary 55

the speed of action on the picker by the lug strap as will be readily appreciated.

I claim:

A lug strap formed with a rounded heel portion and forwardly extending parallel arms, a heel plug fitted within said heel portion and between the said arms, the striking face of said plug having its extreme forward portion at the

intersection of the plug and the uppermost part of the arms, said striking face extending from said forward point downwardly and rearwardly in the form of an arc with no part of said arc forwardly of its top portion, whereby chattering 5 is eliminated in the operation of the lug strap.

W. IRVING BULLARD.
